INSIDE PIPE CUTTER

Vernon Dee Davidson and Milo C. Wilson,
Corpus Christi, Tex.

Application October 5, 1942, Serial No. 460,744

2 Claims. (Cl. 164—0.7)

This invention relates to pipe cutters, and more particularly to a device which may be lowered into a well for severing a pipe therein so that the severed section of the pipe may be removed from within the well.

It is an object of the invention to provide a pipe cutting device having an anchor assembly and a cutter assembly of which the latter is releasable from the former at a desired level in the well and may thereafter be lowered to secure the device in operating position at that level.

Another object is to provide a device of the class described in which the assemblies may be interengaged by lifting of the cutter assembly relative to the anchor assembly and may thereafter be released by rotation of the former relative to the latter.

Another object is to provide a resilient split ring connection between the anchor and cutter assemblies.

A further object is to provide a novel swivel connection between the rotatable and stationary elements of the device.

Still another object is to provide a device which is simple in construction and which is so constructed that difficulty from debris from within the well is minimized.

Still another object is to provide a device which is of rugged construction so that numerous cuts may be made without repair or replacement of the device.

The foregoing are primary objects and will, together with other objects, be more fully apparent from the following description taken in connection with the accompanying drawing in which:

Fig. 1 is an elevational view in section showing one embodiment of the invention, the parts thereof being shown in relative position while the device is being lowered within a well;

Fig. 2 is a sectional view similar to that shown in Fig. 1, but showing the device within a pipe which has been cut thereby;

Fig. 3 is an elevational view of the device, the upper end being shown in section to show the manner of connecting the device to an operating string;

Figs. 4, 5 and 6 are sectional views taken respectively upon lines 4—4, 5—5 and 6—6 in Fig. 1.

In the drawing the numeral 1 refers to a composite cutter assembly which includes an expander 2 swivelly connected thereto and adapted to move within an anchor assembly 3 so that such anchor assembly may be secured at a desired position within a pipe to be cut and the locus of the cutting action is thereby determined.

The cutter assembly 1 includes a body member 4 having a head 5 and a mandrel 6 integral therewith and of a reduced cross section. The mandrel is threaded at 7 at its lower end and has a collar 8 fixed thereon, such collar having external threads 12 thereon. A guide member 9 is attached to the mandrel below the collar 8. The body member 4 and the guide member 9 have coaxial bores 10 and 11 so that flushing fluid may be pumped downwardly through the tool during cutting operations.

The head 5 is slotted at 15 and a cutter blade 16 is mounted in each of the slots upon a pivot 17. Each of the blades 16 has an upward extension or ear 18 to which pressure is applied by means of a compression spring 19 so that the bit 20 at the lower end of each blade is normally retracted inwardly to a position within the peripheral outline of the tool.

Attention is directed to the fact that the shoulder 25 between the head 5 and the mandrel 6 is curvilinear. This is an important feature of the invention since there is eliminated any sharp angular cut in the manufacture of the device, and for this reason the resulting structure is more resistant to torsional and bending stresses at this point to which the device is subjected while in use.

As will more fully appear, the expander 2 is movable axially of the mandrel 6 and in order to limit the upward travel of the expander and associated elements, additional slots 26 are provided in the head 5 intermediate the cutter blades 16. In each of the slots 26 is positioned a stop member 27 which is secured in place by means of a pin 28.

The mandrel 6 is also reduced at 30 to receive an inwardly extending annular flange 31 on sectors 32 which are assembled about the mandrel 40 and held in assembled relation by means of the wedge ring 33. This wedge ring is threaded internally at its lower end to engage the threaded upper end 34 of the sectors 32.

The wedge ring 33 has upwardly extending fingers 35 extending into the slots 15 and having tapered surfaces 37 engageable with the lower tapered and arcuate surface of the cutter blades 16. The fingers 35 therefore rotate with the body member 4 and serve to force the bits 20 outwardly to cutting position in a manner that will presently appear.

As previously explained, the expander 2 is slidably mounted upon the mandrel 6 and is provided with a recess 40 at its upper end to receive the inwardly extending flange 41 on the sectors

32. The interfitting of the expander and sectors is such as to provide a swivel connection so that the wedge ring and sectors are permitted to rotate relative to the expander.

The collar 45 at the lower end of the expander 2 serves as a stop to limit the relative movement between the expander and the mandrel. This stop or collar is engageable with the lower end of the slip member 46 which has upwardly extending fingers 47 provided with outer serrations 48 for engagement with a surrounding tubing to be cut. Such engagement is brought about by relative axial movement between the slip assembly 3 and the expander 2 in such a manner that the fingers 47 are forced outwardly by the expander.

A sleeve member 50 is attached to the lower end of the slip member 46 and terminates interiorly at its lower end in a downwardly tapered surface 52 with which wedging action may be produced upon a split ring 53 which has a complementary exterior surface and which is threaded internally for engagement with the threads 12 upon the collar 8. The split ring 53 is held against rotation by means of a pin 54 in the wall of the sleeve 50.

The stiffness of the ring 53 and its initial dimensions cause the ring to inherently grip the threads on the periphery of the collar 8. For this reason this feature of construction is of importance in that it insures uniform interengagement of the threads whereby a connection between the cutter assembly 1 and the slip assembly 3 is assured.

In the operation of the device above described as an embodiment of the invention, the respective elements are initially in the relative positions shown in Figs. 1 and 3, it being understood that the device is attached to an operating string 55 by means of the pin and box connection 56 (Fig. 3). The bore 10 in the device is a continuation of the bore in the string 55 and it is to be understood that fluid can be pumped therethrough at any time during the lowering and operation of the tool within a pipe to be cut.

When the device has been lowered to a level where the surrounding pipe 57 (Fig. 2) is to be cut, righthand rotation of the operating string will cause relative rotation between the cutter assembly 1 and the slip assembly 3. This is due to the fact that there is sufficient frictional engagement between the slip or anchor assembly 3 and the surrounding pipe or casing 57 to prevent rotation of the slip assembly within the pipe. Such rotation will cause unthreading of the connection between the split ring 53 and the collar 8 whereby the operating string and the cutter assembly 1 will be lowered relative to the anchor assembly 3. When the threaded connection between these parts has been released the entire operating string and cutter assembly can then be lowered, whereupon the expander 2 urges the slip fingers 47 outwardly into fixed engagement with the pipe or casing to be cut.

When the expander 2 has become wedged between the fingers 47, further downward movement of the operating string 55 and the cutter assembly 1 will cause the cutter blades 16 to ride upon the fingers 35 of the wedge ring 33 whereby the bits or blades 20 will be forced outwardly into engagement with the surrounding pipe. It seems apparent that the force with which the bits 20 are fed outwardly will depend entirely

upon the pressure applied downwardly upon the cutter assembly 1. For this reason any desirable cutting action may be brought about by controlling the weight applied upon the cutter assembly and the rate of rotation thereof.

When the device of the invention is to be withdrawn from the well or moved to a different position for a successive cut, the operating string 55 is lifted together with the cutter assembly 1. Such lifting causes the collar 8 to enter the split ring 53 which is limited in upward travel by the stop ring 58. The lifting force then causes the ring 53 to expand so that an interconnection is effected between the cutter assembly 1 and the anchor assembly 3. Attention is directed to the fact that this interconnection is completed without relative rotation of the parts.

The parts of the device are then in the relative positions shown in Fig. 1 as above assumed preliminary to lowering the device into a well. Accordingly, the device may be raised or lowered within the well and additional cuts may be made by a repetition of the operations just indicated.

While the invention has been disclosed by a description of the specific embodiment thereof, it is to be understood that the invention is not confined to such specific embodiment.

Broadly, the invention comprehends a pipe cutting device which may be lowered into a well and operated to sever a pipe by rotation of one portion of the device relative to another.

What is claimed is:

1. In a pipe cutter the combination of, a body including a head and a downwardly extending mandrel, there being vertical slots in said head, cutters pivotally mounted in said slots and having outwardly directed cutter blades at their lower ends, an expander slidably surrounding the mandrel, a reduced section in said mandrel, a wedge ring on said expander having a portion entering said reduced section so as to support said expander in retracted position, a swivel connection between said expander and wedge ring, said wedge ring including upwardly extending fingers to move within said slots and move the cutters outwardly, and slip jaws movable relatively to the expander to anchor the cutter assembly within a pipe to be cut.

2. In a pipe cutter the combination of a body including a head and a downwardly extending mandrel, there being vertical slots in said head, cutters pivotally mounted in said slots and having outwardly directed cutter blades at their lower ends, an expander slidably surrounding said mandrel, a reduced section on the mandrel, said expander including a plurality of sectors surrounding said mandrel and having portions entering said reduced section to support said expander on said mandrel, a swivel connection within the expander for said sectors, the upper end of said sectors forming a threaded area, a wedge ring threadably engaging the threaded area to hold the sectors in position about the mandrel, said wedge ring having upwardly extending fingers to enter said slots and move the fingers outwardly, and slip jaws engageable by said expander and movable outwardly to hold the cutter in a fixed position within the pipe to be cut.
